UNITED STATES PATENT OFFICE.

ROBERT GUNN, OF BUFFALO, NEW YORK.

DESIGN FOR A BRACKET.

SPECIFICATION forming part of Design No. 25,027, dated December 31, 1895.

Application filed November 20, 1895. Serial No. 569,585. Term of patent 14 years.

To all whom it may concern:

Be it known that I, ROBERT GUNN, a citizen of the United States, residing at Buffalo, in the county of Erie and State of New York, have invented and produced a new and original Design for Brackets, of which the following is a specification, reference being had to the accompanying drawing, which is a perspective view of my invention.

The bracket consists of bottom and top plates 1 3, respectively, joined together in the longitudinal center of each by a vertical plate 2. The top plate 3 and the vertical plate 2 are of equal length, while the bottom plate 1 has projecting ends 5, which may be rounded, and are provided with slight elevations, perforated as shown at 6. The bottom plate 1 ex-

tends from the center downwardly and outwardly, thus forming an angle at the center. The top plate 3 is flat and narrower than the bottom plate 1 and has ears 4 projecting from each edge, through which are holes 7. The vertical plate 2, which is wider at each end than at the center, may be provided with elongated openings 8. 25

I claim—

The design for a bracket herein shown and described.

In testimony whereof I have hereunto set my hand and affixed my seal.

ROBERT GUNN. [L. S.]
